PROPYLUREA-MERCURY COMPOUNDS AS
DIURETICSEmanuel Leon Foreman, Alhambra, Calif., as-
signor to Lakeside Laboratories Inc., a corpo-
ration of WisconsinNo Drawing. Application August 31, 1949,
Serial No. 113,493

10 Claims. (Cl. 167—71)

1

This invention relates to propylurea compounds containing mercury and diuretic compositions containing the same.

In various types of heart diseases, particularly congestive heart trouble, the patient becomes bloated due to sodium in the form of salt and thus water gathering in the tissues. In order to relieve this condition, various compositions have been prescribed containing diuretic compounds. These diuretics serve to excrete water and salt from the kidneys and thus from the tissues so that the heart condition is relieved. Many of the former diuretic compounds were aromatic or aliphatic amines or amides, particularly aliphatic amines or amides. Inorganic mercury compounds have been used as diuretics for many years, but only recently have organic mercury compounds been used. The early organic mercury compounds were amines and amides containing a mercury atom. Most of these prior diuretic compounds, particularly of the mercury type, were dangerous to use as they sometimes caused death by stopping the heart. When they were injected into the veins or the muscles, they sometimes destroyed or at least caused severe irritation of the tissues. This was particularly true where the injection into the muscle accidentally contacted fatty tissues.

The new compounds of this invention have essentially the following structural formula:

wherein R is a member of the class consisting of hydrogen and alkyl, and X is a non-carbon, or inorganic, atom of negative valence, or a group including such an atom bonded directly to the mercury atom. More specifically, X is either halogen, hydroxyl, oxy-acyl, the residue of an acidic nitrogen compound having a replaceable hydrogen on the nitrogen atom, or the residue of an alkyl thiol acid wherein the sulfur is bonded directly to the mercury. Those compounds wherein X is either halogen, hydroxyl, oxy-acyl, or the residue of an acidic nitrogen compound having a replaceable hydrogen on the nitrogen atom so that the nitrogen is bonded directly to the mercury atom are disclosed and claimed in the copending application of Ralph L. Rowland, Serial No. 113,494, filed August 31, 1949, now abandoned.

The alkyl thiol acid used in preparing the thio-mercurated propylurea compounds has a replaceable hydrogen on the sulfur atom so that

2

the sulfur is bonded directly to the mercury atom in the resulting mercurated propylurea compound. The preferred compounds of this invention have the following structural formula:

wherein R and R' are each either hydrogen or alkyl. In the preferred cases, R and R' are each an alkyl group containing from 1 to 5 carbon atoms. It is preferred that the alkali metal salt of the acid, such as the sodium or potassium salt, be used as a diuretic as these salts are water soluble.

Examples representing the compounds and their methods of preparation are as follows:

Example 1

C₇H₁₄N₂O₄SHg M. W.=423

To a refluxing solution of 100 g. of allyl urea and 600 ml. of absolute methanol there was added with stirring a suspension of 319 g. of mercuric acetate and 600 ml. of absolute methanol and 60 ml. of glacial acetic acid; complete solution resulted. After 6 hours of refluxing, the solution was cooled and clarified by filtration. To this solution there was added 50 g. of sodium chloride and 240 ml. of water. After a short time a heavy white precipitate settled out. This precipitate, which was 3-chloromercu-2-methoxy-propylurea, was filtered, washed and dried. 100 g. of this compound and 400 ml. of water and 85 g. of 10% sodium hydroxide was added to a solution of 25 g. of thioglycolic acid, 100 g. of 10% sodium hydroxide solution and 140 ml. of water. This solution was clarified by filtration through a bed of filter aid and then acidified with 29 ml. of glacial acetic acid. The white granular solid which precipitated was filtered, washed and dried (93 g. or 80% yield). The substance melts at approximately 108–112° C. and on further heating resolidifies and finally decomposes at 138–139° C.

Analysis: Calc: N, 6.62; Hg, 47.5. Found: N, 6.42; Hg, 47.6.

The product is readily soluble in water on addition of sodium hydroxide and a 10% solution can be prepared at physiological pH which, therefore, is suitable for parenteral use.

a thio-mercurated propylurea having the structural formula:

wherein R and R' are each a member of the class consisting of hydrogen and an alkyl group containing from one to five carbon atoms, and A is a member of the class consisting of hydrogen and alkali metal.

8. As a diuretic, a pharmaceutical carrier and a thio-mercurated propylurea having the structural formula:

wherein R is methyl, R' is hydrogen, and A is a member of the class consisting of hydrogen and alkali metal.

9. As a diuretic, a pharmaceutical carrier and a thio-mercurated propylurea having the structural formula:

wherein R is methyl, R' is methyl, and A is a 30

member of the class consisting of hydrogen and alkali metal.

10. As a diuretic, a pharmaceutical carrier and a thio-mercurated propylurea having the 5 structural formula:

10 wherein R is methyl, R' is propyl, and A is a member of the class consisting of hydrogen and alkali metal.

EMANUEL LEON FOREMAN.
